UNITED STATES PATENT OFFICE.

JOHN H. BURKHOLDER, OF ASHLAND, OHIO, ASSIGNOR TO THE ELITE MANUFACTURING COMPANY, OF ASHLAND, OHIO, A CORPORATION.

CORNER-BRACKET FOR BUILDERS' SCAFFOLDS.

1,238,724.

Specification of Letters Patent. Patented Aug. 28, 1917.

Application filed February 16, 1917. Serial No. 149,005.

To all whom it may concern:

Be it known that I, JOHN H. BURKHOLDER, citizen of the United States, residing at Ashland, in the county of Ashland and State 5 of Ohio, have invented certain new and useful Improvements in Corner-Brackets for Builders' Scaffolds, of which the following is a specification.

This invention pertains to a corner 10 bracket for builders' scaffolds, constructed and adapted to operate substantially as shown and described and particularly pointed out in the claims.

In the accompanying drawings, Figure 1 15 is a plan view of the bracket in using position on the corner of a building shown in cross section and disclosing planks crossed at their ends on the bracket at the corner. Fig. 2 is a reduced view of Fig. 1, but showing more of the building and at least one side bracket, and Fig. 3 is a side elevation of Fig. 2.

Fig. 4, Sheet 2, is an enlarged perspective view of the bracket supported on a corner 25 as in Fig. 1, and Fig. 5 is a front view of a portion of the bracket with the brace member broken off near its lower extremity and designed more especially to show the divided or bifurcated shoe of the brace.

30 Numerous scaffold supports of widely different constructions are known to have been patented and more or less practically developed and in use, but a support of the kind herein shown and described is broadly new 35 so far as I know or believe.

It will be observed, first, that the present bracket is essentially a corner engaging device and adapted to receive the ends of planks projected from two sides at right 40 angles to each other into meeting relations on the bracket. The prevailing types of scaffold supports above acknowledged are made to affix or engage with one side of a building, and which have the ends of the 45 planks projecting over and across the same more or less and sometimes to such extent that the weight of the carpenter on the exposed end will overbalance the plank and serious accident is liable to follow. My invention is designed to anticipate this common danger and to insure the safety of the workmen so far as a perfectly secure footing 50 is concerned. Obviously, also, a corner bracket of this kind will render it unnecessary to employ as many side brackets as for-

merly and thus it contributes to both economy and safety in scaffold work.

Referring to the drawings, it will be seen that the bracket consists, in its broader sense, of two horizontal parts or arms *a*, an inclined brace *b* and a linked connection 60 10 between said parts.

The said arms are of suitable length and strength and may be solid or tubular and of wood or metal, but metal preferably, and the brace *b* is pivotally and foldably engaged between the outer ends of said arms by a bolt 2. The said brace also has its upper end 3 projected somewhat above said arms to serve as an outer guard for the plank 70 4 of the scaffold, and a special bifurcated or split shoe 5 fixed upon the lower end of said brace is adapted to seat upon or across the corner or angle of the building with its toes upon opposite sides thereof and support 75 said brace against lateral movement as seen in plan, Fig. 1.

The horizontally disposed supporting arms *a* are provided with suitable means for securing the ends thereof upon or to studing or other portions of the frame work of the building, and in this instance the said means are shown as of the nature of metallic clips *c* having keepers 6 within which the ends of the arms are confined by heavy rivets 80 or bolts 7 through said keepers and clips and said arms, so that while a somewhat flexible connection of the said parts is made the arms are held firmly in position on the building and there is no danger of their being 85 drawn out or broken away in use. The extremities of the clips *c* have keyhole slots 9 for spikes or nails to fasten them on the building, and the said clips are placed transversely to the said arms and the direction of 90 strain.

Now, it will be noticed that the shoe or extremity 5 of brace *b* is designed to spread its toes or points 8 across the corner of the building to the two sides thereof so that the 100 said brace will be positively confined to its right working relation on the building and cannot escape therefrom in use, but it will also be observed that there are no local means on which said shoe engages or rests 105 nor is it fastened to the building in any way, but I do provide a stop or support in the nature of a suspensory medium consisting in this instance of a link bar 10, chains 12 and a lock plate 14 connecting said 110

parts. The chains are slidably engaged at one end on or over the arms *a* next to the building and with the lock plate 14 at their other ends and are in V-shaped relations in 5 use. The said plate has a middle transverse slot, and the link bar 10 has teeth at intervals on its edge adapted to engage in said slot and to provide the necessary adjustment to adapt the device to the building and to 10 give the brace its proper working angle or inclination, say of 45 degrees downward and inward in respect to the horizontal position of the arms.

It will be noticed that the two arms *a* 15 are clamped to opposite sides of the building and that the chains engage over said arms in such manner and in such relation to their inner ends that the greater the weight or strain downward on brace *b* the 20 greater the tendency of the chains to pull the arms *a* toward each other and thereby actually tighten them against the sides of the building in an embracing position. It will be especially noticed also that the sus- 25 pensory means for the extremity of the brace bar are the exclusive means of vertical support or of preventing the foot of the brace from slipping down.

The device as thus shown is foldable with 30 the arms and the brace and link connections in compact relation for transportation or storage.

Of course I do not claim that the suspensory means comprising the toothed link 35 bar 10 and the chains 12 are the only means that may be employed in the connection shown. In fact they are rather suggestive than exclusive, and any sufficient or satisfactory alternative may be substituted 40 therefor. But it is desirable that the connection be flexible and adjustable as to length and that it should have the V arrangement of the branches or chains, and that engagement be made with the lower 45 extremity of bar *b*. Of course the said shoe 5 is practically a portion of brace *b*, and whether it be in one or two pieces is im- material, but in one piece is preferable, as shown with the toes or points 8 in V-shaped 50 relation as shown.

Obviously several of the parts herein shown and described may be substituted by practical equivalents, such, for example, as the clips *c*, in lieu of which I may use suitable bolts engaged directly through the slots or extremities of the arms *a*, or other means that will make a firm engagement with the building and said arms, and any suitable link connection may be substituted for the 60 links 10 and 12, such as a chain suitably connected up at its ends with the parts *a* and 5. These are details in which I do not care to be specifically confined since the essence of the invention subordinates such 65 details in the larger conception of a braced

and suspensory medium which contemplates only two points of actual connection with the building, and these for the arms *a* are on the same horizontal plane.

What I claim is:

1. A scaffold bracket for corner use comprising a pair of arms adapted to be firmly fixed at their rear ends to the sides of a building and a brace connected with the outer ends of said arms and provided with 75 a free end adapted to engage the corner of the building, and suspensory means connecting said free end of the brace with the said arms respectively. 70

2. A scaffold bracket as described, comprising a pair of arms operatively connected at their outer ends and adapted to be clamped to the sides of a building at their inner ends to provide a firm support, and a brace engaged between the connected ends of 80 said arms and provided with a forked ex- tremity at its inner end adapted to engage the corner of a building, and a flexible sus- pensory connection between the said inner end of said brace and said arms. 85

3. A bracket for builders' scaffolds consisting of two arms and a brace pivoted between the outer ends thereof, means to firmly se- 90 cure the inner ends of said arms on different sides of a building to carry the weight of the scaffold and means on the inner and lower end of said brace to engage the corner of a building, and a flexible connection be- 95 tween the inner and lower end of said brace and the inner ends of said arms adapted to draw said arms toward each other under down pressure on said brace. 100

4. A scaffold bracket having two supporting arms pivotally connected at their outer ends and means on the inner ends thereof to 105 firmly support said arms against the sides of a building, a brace pivoted between the outer ends of said arms and having a di- vided extremity adapted to bear against op- 110 posite sides of a building at the corner there- of, a link connection between said divided extremity and said arms and means in said connection to lengthen and shorten the same.

5. A bracket for builders' scaffolds comprising two arms and means at the inner 115 ends of said arms to removably support the same on different sides of a building at a corner thereof, a brace pivotally engaged between the outer ends of said arms and pro- jecting above the same and having a split 120 shoe at its free lower end, and a linked con- nection between said shoe and said arms respectively.

6. A builder's scaffold bracket comprising two parallel arms adapted to form a hori- 125 zontally disposed "V" in use and a single brace pivoted between the outer ends of said arms and adapted to occupy a sub- stantially forty five degree angle downward and inward in operation, and suspensory 130

means between the inner end of said brace and the inner ends of said arms, said suspensory means being branched to form a "V" substantially at its upper portion and 5 having one branch connected with each arm, whereby a tendency is induced to pull said arms toward each other under a load on the scaffold.

7. A bracket for a builder's scaffold having horizontally disposed arms and means 10 to fix the same on the sides of a building, a

brace pivoted between the outer ends of said arms and having a divided extremity adapted to seat on the corner of a building relatively below said arms, and suspensory means 15 for said brace engaged with both said arms near their inner ends and with the divided extremity of said base.

Signed at Ashland, in the county of Ashland and State of Ohio, this 15th day of 20 December, 1916.

JOHN H. BURKHOLDER.
